UNITED STATES PATENT OFFICE.

EDWARD CALUSINSKI, OF CHICAGO, ILLINOIS.

BED.

1,413,455.

Specification of Letters Patent. Patented Apr. 18, 1922.

Application filed March 5, 1921. Serial No. 449,920.

To all whom it may concern:

Be it known that I, EDWARD CALUSINSKI, a citizen of the United States, and a resident of the city of Chicago, in the county of Cook and State of Illinois, have invented a new and useful Improvement in Beds, of which the following is a full, clear, and exact description.

My invention relates to improvements in beds and it consists in the combinations, constructions, and arrangements herein described and claimed.

An object of my invention is to provide a bed that is constructed to permit positioning of the mattress supporting means embodied therein in various positions in order that a sick person may be supported thereby to receive proper treatment and in order that the maximum of comfort may be provided for the patient.

A further object of my invention is to provide a device of the type described in which the means for adjusting the mattress supporting member to support a patient in various positions, as for instance in sitting, semi-reclining, and recumbent positions, can be operated without removing the patient from the bed.

A further object of my invention is to provide a device of the type described in which means are provided for adjusting independently of one another several portions of the mattress supporting member, as for instance, the head and foot portions.

A further object of my invention is to provide in a device of the type described, a foldable table adapted to be extended and maintained in operative position close to the patient or to be folded and moved out of the way when in inoperative position.

A further object of my invention is to provide a device of the type described that is relatively simple in construction and operation, and not likely to get out of order easily.

Other objects and advantages will appear in the following specification, and the novel features of the invention will be particularly pointed out in the appended claims.

My invention is illustrated in the accompanying drawings, forming part of this application, in which—

Figure 1 is a side elevation of the device, showing a mattress supporting member embodied therein in tilted position and the

table portion of the device in extended or operative position.

Figure 2 is a view similar to Figure 1, showing the mattress supporting member in another position and the table in its folded or inoperative position.

Figure 3 is an end view of a portion of the device.

Figure 4 is a section along the line 4—4 of Figure 2.

Figure 5 is an enlarged section along the line 5—5 of Figure 2, and

Figure 6 is a plan view of the fragmentary portion of the device shown in Figure 5.

In carrying out my invention, I provide head posts 1—1 having secured thereto in any suitable manner, an end bar or frame member 2 and foot posts 3—3 connected by an end frame member 4. The end frame members 2 and 4 are connected in the usual manner by the side bars or frame members 5 and 6, so that a rigid bedstead frame is provided.

A mattress support comprising parallel end bars 7 and 8 having connected sections 9, 10, and 11 of wire netting or the like interposed therebetween and connected thereto by springs 12—12 is movably supported at its ends substantially parallel with the rigid frame, and in a higher plane by means which will be hereinafter described in detail. It will be noted that the adjacent ends of the sections 9 and 10 are hingedly connected to one another at 13 and that a plurality of connector links 14, such as shown in Figures 5 and 6 are interposed between the adjacent ends of the sections 10 and 11. Each of the links 14 is formed with a tongue 15 at one end thereof and with a slot or socket 16 in its opposite end. The tongue 15 of one of the connectors is arranged to enter the socket 16 of the adjacent connector and is secured therein by a pin 17. The contiguous walls of the tongue 15 and the slot 16 are straight and abut one another so that when a plurality of the connecting links 14 are secured together in the manner described, adjacent links are permitted to move downwardly under stress at the point of their connection with one another and are prevented from moving upwardly out of a horizontal plane at the same point on account of the engagement of the tongues 15, respectively, with the corresponding sockets 16. The connectors 14 are each formed with diametrically

65

75

opposed lateral extensions 18—18, each having an opening 19 therein adapted to receive the ends of wires 20 composing the woven wire body portions of the sections 10 and 11.

5 The tongue 15 of one end connector in the series provided is secured by one of the pins 17 in a socket 21 of an end plate 22 that has an integral depending lug 23. A chain 24 is connected at one end to the depending lug 23 and at its other end to a lug or bracket 25 that is secured at 26 to the side bar 5, as clearly shown in Figure 1.

10 A tongue 27 of an end plate 28 is secured in the socket 16 of the other end connector in the series by one of the pins 17. The end plate 28 is formed with a depending lug 29 and a chain 30 that is similar to the chain 24 and is connected at 31 to the lug 29 and has its other end connected to the side rail 6.

15 The end plates 22 and 28 are each provided with diametrically opposed openings 32—32 adapted for connection, as by means of links 33—33 with the adjacent portions of the mattress supporting sections 10 and 11.

20 To the end that the mattress supporting frame may be supported normally in a higher plane parallel with the rigid bedstead frame so that the sections thereof can be tilted in order to support a patient in various positions with a maximum degree of comfort, as for instance in sitting, reclining and recumbent positions, and that the sections 9 and 11 can be tilted independently of one another, I provide a pair of parallel supporting members 34—34 which are in effect bell crank levers. The shorter arms of the bell crank levers are rigidly secured at 35 in any suitable manner to the end frame member 7 adjacent and end thereof. The bell crank levers 34—34 have their opposite ends rigidly secured at 36 to a transverse thrust bar 37 that has a length equal to that of the end bar 7 and is disposed parallel therewith. The bell crank levers 34—34

30 are respectively fulcrumed within corresponding longitudinally extending vertical slots 38—38 in the side members 5 and 6, being rotatably mounted on guide pins 39—39 that project respectively through horizontal slots 40—40 in the side bars 5 and 6 and have their inner ends fast in lateral extensions 41—41 of a transverse guide bar 42. The guide bar 42 is fashioned intermediately to provide a depending boss 43 provided with a threaded opening 44 adapted to receive a screw 45 that constitutes a portion of a sleeve 46 rotatably mounted on a shaft 47 and being journalled at 48 adjacent its outer end in the end bar 4. The shaft 47 extends

40 the length of the rigid frame and has its other end journalled at 49 in the end bar 2.

45 In supporting the section 11 of the mattress supporting member in the manner indicated, I provide a pair of relatively long arms 50—50 which are rigidly secured at

their upper ends to the end member 8 at the ends thereof and have their other ends disposed in longitudinally extending slots 53—53 in the side frame members 5 and 6 at the head end of the bed and rotatably mounted on guide pins 51—51 that are disposed in horizontal aligned slots 52—52 through the side frame members 5 and 6 intermediate the length thereof and are slidable along the slots. Arms 54—54 are pivoted at 55—55 at their upper ends to the arms 50—50 and at 56—56 to the upper ends of rocker arms 57—57. The latter are intermediately rigidly mounted at 58—58 between pairs of upstanding lugs 59—59 integral with the side frame members 5 and 6 on a transverse rock shaft 80 so that the rocker arms 57—57 can be moved about the shaft 80 through the slots 53—53. The rocker arms 57—57 are pivotally connected at 60—60 to corresponding ends of U-shaped links 61—61 which are respectively disposed within the slots 53—53 and formed with arms 62—62 extended and pivotally connected at 63—63 with links 64—64. The latter are entirely disposed within the slots 53—53 for slidable movement by means of guiding and retaining pins 65—65 that are projected through longitudinal slots 66—66 in the links 64—64 and have their ends secured in the walls of the slots 53—53. The links 64—64 are pivotally connected at their other ends as at 67—67 with connecting bars 68—68 which are in turn pivotally connected at 69—69 with the members 50—50 at spaced distances from the lower ends thereof.

50 The bell crank levers 34—34 are likewise braced by connectors 70—70 pivoted at their upper ends at 71—71 to the bell crank levers and pivoted at 72—72 between pairs of lugs 73—73 that are formed integrally with links 74—74 having their lower end portions pivoted at 75—75 between the walls of the slots 38. The connectors 70—70 have their lower ends abutting against shoulders or stop members 75'—75' provided between the lugs 73—73 integral with the connectors 74—74 so that the movement of the same about their pivots 72—72 in one direction is limited. Transversely extending stop pins 76—76 are provided with their ends fast in the walls of the slots 38—38 so that the movement of the connectors 74—74 about their pivots 75—75 downwardly is limited.

55 From the foregoing description of the various parts of the device, the operation thereof may be readily understood. The device is particularly suitable for use in hospitals and in caring for sick patients, since they can be supported in various positions in order that the proper treatment may be administered and in order to provide the maximum of comfort. The positions of the mattress supporting member may be changed without removing the patient from the bed.

The shaft 47 is formed with a non-circular member 77 adapted to a spanner or socket wrench or the like and rotation of the shaft 47 will occasion a like movement of the portion thereof adjacent to the head end of the device that is formed to provide a worm 78. A gear 79 is rigidly mounted on a transverse rock shaft 80. The worm 78 is maintained in engagement with the gear 79 by a U-shaped yoke or hanger 81 that is hung from the transverse shaft 80. Consequently, operation of the shaft 80 rocks the rocker arms 57-57 so that the latter and the links 54-54 are moved into alinement to support the section 11 in the position shown in Figure 1. The links 64-64 will also be moved along the slots 53-53 and the bracing members 68-68 will assume the positions illustrated in Figure 1. The section 9 may now be tilted by rotating the sleeve 46 which is formed with a non-circular end portion 82 adapted to a wrench or key. It is obvious that rotation of the sleeve 46 and the integral screw 45 will cause the guide bar 42 to be moved along the slots 40-40 and the section 9 will be tilted to the position shown and will be supported in that position by the bell crank levers 34-34 which are in turn braced by the connectors 70-70 and 74-74. When the several sections of the mattress supporting members are in the position shown in Figure 1, a patient may be supported in a sitting position. When the several sections are in the position shown in Figure 2, the device is suitable for use as a bed.

In Figure 1, I show a folding table that is embodied in the device. Two article supporting members 84 and 85 are hingedly connected at 83 so that the member can be folded together. A supporting arm 86 is pivoted at 87 to a lug 88 that depends from the under surface of the table member 85

and at 89 to one of the arms 50. A substantially L-shaped connector 90 is pivoted at 45 one end at 91 adjacent the rear edge of the member 85 and has its other end bent to slidably engage a slot 92 in the arm 86. The connector 90 is connected to the arm 50 by a link 93 that has one end pivoted to the arm 50 and its other end pivoted at 94 to the L-shaped connector 90. It is thus obvious that the table can be moved into position close to a patient who is supported in a reclining position. When not in use, the table 55 can be folded and moved out of the way as shown in Figure 2.

I claim:

1. A device of the character described comprising a rigid frame, a flexible mattress supporting member comprising three sections, said sections being hinged together, means carried by said rigid frame for swinging one of said sections at an angle to a horizontal plane, means carried by said rigid frame for swinging the other two sections at an angle to each other and the end section thereof at an angle to a horizontal plane, and worm gears associated with said first and second named means and operable from one end of said rigid frame for selectively actuating said first and second named means.

2. A device of the character described comprising a rigid frame, legs for supporting said frame, a mattress supporting member comprising three sections, said sections being hinged together, means carried by said rigid frame for swinging one of said sections at an angle to the plane of said frame, means carried by said rigid frame for swinging the other two sections at an angle to each other and to the first named section, and means operable from one end of said rigid frame for selectively actuating said first and second named means.

EDWARD CALUSINSKI.
